UNITED STATES PATENT OFFICE.

JAMES A. RODMAN, OF SHERARD, MISSISSIPPI, ASSIGNOR OF ONE - HALF
TO JOHN H. SHERARD, OF SHERARD, MISSISSIPPI.

CUTTING APPARATUS FOR HARVESTERS.

No. 840,518.

Specification of Letters Patent.

Patented Jan. 8, 1907.

Application filed September 7, 1905. Serial No. 277,338.

To all whom it may concern:

Be it known that I, JAMES A. RODMAN, a citizen of the United States, residing at Sherard, in the county of Coahoma and State of Mississippi, have invented a new and useful 5 Cutting Apparatus for Harvesters, of which the following is a specification.

This invention relates to cutting apparatus for mowing-machines and other harvesters; 10 and it has particular reference to that class which is known as "endless" cutting apparatus, the same consisting of an endless chain equipped with cutters or cutting-blades which under the construction of the present 15 invention are made to coöperate with each other in the sense that the cutters borne by the upper lead of the endless chain are made to coöperate with the cutters borne by the lower lead of said chain.

20 The objects of the present invention are to simplify and improve the construction and operation of this class of devices; and with these and other ends in view, which will readily appear as the nature of the invention 25 is better understood, the same consists in the improved construction and novel arrangement and combination of parts, which will be hereinafter fully described, and particularly pointed out in the claim.

30 In the accompanying drawings has been illustrated a simple and preferred form of the invention, it being, however, understood that no limitation is necessarily made to the precise structural details therein exhibited, 35 but that changes, alterations, and modifications within the scope of the invention may be made when desired.

In said drawings, Figure 1 is a front elevation of a cutting apparatus constructed in 40 accordance with the principles of the invention. Fig. 2 is a top plan view of the same. Fig. 3 is a transverse sectional view enlarged. Fig. 4 is a perspective detail view of one of the links of the endless chain and a blade or 45 cutter detached from said link.

Corresponding parts in the several figures are indicated throughout by similar characters of reference.

A driven shaft 1, which is supported for 50 rotation in the machine to which the invention is applied, supports an arm 2, the outer extremity of which carries the cutter-bar 3, which is bolted to or otherwise suitably connected therewith. The cutter-bar supports

a housing composed of two forwardly-extending spaced plates 4 and 5, the forward edges of which are provided with flanges 6 and 7, which are spaced so as to form between said flanges a slot 8. The ends of the housing-plates 4 and 5 are offset or beveled, as shown 55 at 9.

Upon the inner end of the cutter-bar is supported a bracket member 10, having studs or pintles 11, one above and the other below the cutter-bar, upon each of which 60 studs is journaled a guide-roller 12. Another bracket member 13 is secured upon and extends outwardly from the outer end of the cutter-bar, said bracket member having pintles 14, upon which guide-rollers 15 are 65 supported for rotation, one above and the other below the cutter-bar. The bracket member 13 is extended beyond the rollers 15 70 and is provided with a longitudinal slot 16, in which is secured an adjustable pindle 17, 75 disposed intermediate the planes of the rollers 15 and carrying a tightening-wheel 18, the lower edge of which is below the horizontal plane of the cutter-bar and in approximate alinement with the lower edges of the 80 lower guide members 12 and 15. A sprocket-wheel 19 is secured upon the shaft 1 in alinement with the tightening-wheel 18 and with its lower edge in the horizontal plane of the 85 lower edge of the wheel 18.

A chain C of suitable length is made up of a plurality of cutter-carrying links 20, each of which is provided with a sprocket-engaging aperture 21, a cross-bar 22, spaced from the body of the link by lugs 23, and a hook member 24, adapted to engage the cross-bar of the next adjoining link. Each link is provided with a recess 25 for the reception of the inner end of a blade or cutter 26, which is secured in said recess by rivets or other suitable 90 means in such a manner as to be flush with the inner surface of the link—that is to say, the surface which faces the opposite lead of the chain. This chain is guided over the sprocket-wheel 19 and the tightening-wheel 100 18 between the guide-pulleys 11 and 15 and between the housing-plates 4 and 5 in such a manner that the blades will project through the slot 8 between the flanges 6 and 7 of said housing-plates, as will be clearly seen by reference to Fig. 3 of the drawings. Each of the blades is provided with an oblique cutting edge 27. 105

In Figs. 1, 2, and 3 of the drawings has been shown guard-fingers 28 of ordinary construction, arranged to coöperate with the cutters; but these guard-fingers may be dispensed with when desired.

From the foregoing description, taken in connection with the drawings hereto annexed, the operation and advantages of this invention will be readily understood by those skilled in the art to which it appertains. The construction is simple and inexpensive, and the device is simple and practical in operation.

The supporting-shaft 1 is not necessarily a driven shaft, as stated at the outset; but it may be in the nature of a supporting-shaft only, in which event it follows that motion will be transmitted from some driven part of the machine with which the device is connected direct to the sprocket-wheel 19. The latter has been shown as provided with a flange 30 to obviate any possibility of the cutter-carrying chain being pushed out of engagement with said sprocket-wheel.

By loosening the pintle which carries the chain-guiding wheel 18 the latter may be moved in an inward direction, thus slackening the chain and permitting links to be removed from the latter when necessary for repairs, sharpening of the blades, or other reasons.

The beveled or offset ends 9 of the housing-plates will guide the chain-links in connection with the guide-rollers 12 and 15 so as to avoid any possibility of the links sticking or hanging at these points.

By locating guide-pulleys, as 12 and 15 15, respectively, above and below or adjacent to the upper and lower sides of the cutter-bar 40 and by locating the sprocket-wheels 18 and 19 with their lower edges below the plane of the cutter-bar the cutter-carrying chain will be guided more nearly in a straight line and without sudden sharp twists and deflections,

such as would necessarily occur if supporting-pulleys for the chain or sprockets for said chain were supported above or adjacent to one side of the cutter-bar only. This obviously is an advantage, inasmuch as it reduces the liability of strain and breakage.

Having thus described the invention, what is claimed is—

A cutting apparatus for harvesters comprising a cutter-bar having forwardly-extending housing-plates provided with spaced flanges and beveled ends, bracket members connected with the ends of the cutter-bar, a pair of rollers supported upon each bracket member, one roller of each pair being above and one below the cutter-bar and adjacent to the beveled ends of the housing-plates, a chain-tightening wheel supported adjustably by the bracket member at one end of the cutter-bar, a pintle supporting said wheel and being adjustably attached to the said bracket member and being adapted to be moved in a line midway of the centers of the pairs of rollers, the lower edge of said tightening-wheel being below the cutter-bar and in approximate alinement with the lower edge of the lower rollers, a supporting-bar connected with the inner end of the cutter-bar, a shaft extending through said bar, a sprocket-wheel supported for rotation upon said shaft with its lower edge in substantial alinement with the lower edges of the lower rollers, and a cutter-carrying chain supported by the sprocket-wheel and the tightening-wheel, the links of said chain being guided between the guide-rollers and between the housing-plates connected with the cutter-bar.

In testimony that I claim the foregoing as my own I have hereto affixed my signature in the presence of two witnesses.

JAMES A. RODMAN.
